METHOD OF AND APPARATUS FOR PRODUCING STACKS OF FOLDED STRIPS OF PAPER FOR USE WITH RECORDING MACHINES

Application filed January 3, 1929. Serial No. 330,007.

In the operation of our various inventions relating to the use of back and forth folded tape with recording instruments, such for example as stock tickers, we have found it desirable to provide an expeditious and economical method of and apparatus for according suitable folds to paper, so that when cut into strips of the desired width it will produce the folded tape required in our practice.

Therefore, we have devised a machine which is capable of indenting paper that is drawn over rollers therein with a degree of tension that permits indents or creases to be created, and that allows the indented paper to fall into a folded stack, whereafter such stack can be sheared to divide it into a number of stacks of folded tapes or strips.

Other features and advantages of our invention will hereinafter appear.

20 In the drawings:

Figure 1 is a side elevation of our improved paper indenting machine.

Fig. 2 is a horizontal section thereof, taken on the line 2-2 of Fig. 1.

25 Fig. 3 is an enlarged section on the line 3-3 of Fig. 4.

Fig. 4 is a top plan view.

Fig. 5 is a detail of the paper gripping and releasing means.

30 Fig. 6 is a detail of a blade with a serrated edge, forming a part of the paper indenting and fold creating means, and

Fig. 7 is a detail of a similar blade, having an even edge.

35 In said drawings let 1 indicate the frame of the machine, in which are journalled the shafts 2, 3, carrying the rollers 4, 5 in horizontal parallelism, the opposed surfaces of said rollers being in juxtaposed relation. A

40 roll of paper 6, carried by a shaft 7 which is journalled in bearings 8 that are supported by the frame members 9, supplies the web 10 that is intended to be passed between the rollers 4, 5 for the indenting and folding operation to be performed thereon.

The machine frame is provided with a table 11 which serves to receive the folded paper, said table being supported on horizontal frame members 12, elevated upon legs 13, but

50 the frame members 9, which support paper

roll bearings 8, are located in a plane below said members 12.

Mounted in bearings 14 upon members 12 is a roller 15, whose shaft 16 carries a pulley 17, that is connected by a belt 18 with a pulley 19, the shaft 20, for pulley 19 being journalled in the frame and located above the horizontal plane occupied by the rollers, 4, 5.

Resting on the web 10, above roller 15 is a roller 21, which is journalled in links 22 that are pivoted to the frame uprights 23, whereby said roller imposes its weight against the web, thereby supplying sufficient tension at this point to steady the draft upon roll 6.

The web 10 leaving roller 15, is allowed to fall into a loop 10', whose upwardly directly portion is carried over a guide bar 24 that is secured, at an elevated position, to the uprights 23, a hinged shoe 25 lightly pressing the web to bar 24, to frictionally steady the web at this point.

The drive means for the moving elements of the machine comprise a pulley, 26, here shown as operated by means of a belt 27 that is connected with a motor 28, said pulley 26 having a stub shaft 29 journalled in bearings 30 carried by a horizontal member 31 of the frame. A pinion 32 on shaft 29 meshes with a gear 33 on shaft 2, to rotate the latter, and roller 4 and said gear 33 is in mesh with a gear 35 on shaft 3, whereby said gear 35 with roller 5 is caused to rotate in a direction opposite to that of shaft 2 and roller 4.

The means whereby drive is communicated to belt 18, for feeding web 10 into its gravity loop 10', are as follows:

A pinion 36, whose shaft 37 is suitably journalled in the frame, is in mesh with gear 35, above the latter, and also meshes with a pinion 38 carried by shaft 20 for pulley 19, thereby completing the train for the operation of belt 18. Also the shaft 20 for pulley 19 carries a steel drum 39, which has adjacent peripheral relation with the felt surface 40 of a roller 41 that is carried by a shaft 42; said shaft being suitably journalled in brackets 43, which are pivotally pendant from a shaft 44 that is journalled in the frame. A frame portion 44' supports the bracket 43, and is provided with adjustment means 45, extend-

ing through block 46, for the purpose of regulating the degree of tension with which the felt surface 40 exerts frictional contact upon the web 10.

It will be noted that the web 10 follows in a vertical line from its point of engagement between the peripheral surfaces of drum 39 and felt surface 40 to the point of its entry between the peripheral surface of rollers 4 and 5, where said web is to become indented in creating the folds thereof.

For the performance of the indenting operation each of the rollers 4 and 5 is equipped with a socket and a blade in opposite, radial alignment, the arrangement of these elements on the pair of rollers being such that the blade on each roller will enter the socket in the other roller when in the opposite rotation of the rollers the respective blades and sockets approach their position of registry at opposite sides of web 10 while said web is passing between the rollers.

The blade 47 for each roller is secured in a strip 48 that is fitted in a recess 49 sunk longitudinally in the roller periphery, set screws 50 being employed to firmly secure the strip 48 in said recess.

The socket in each roller is composed of a recess 51 formed within the roller periphery and a pair of jaws therein, the jaw having the reference character 52 being fixed within the recess, and the other jaw 53, being pivotally supported in the recess by a shaft 54 to which an arm 55 is attached, outside the roller end. Said arm 55 has a roller 56 mounted thereon that engages the surface of a cam 56' centered on shafts 2 and 3 respectively, and attached to the frame, for the operation of the movable jaw. A spring 57, having a fixed connection 58 at one end, engages the movable jaw 53 at its other end 59 to tensionally draw said jaw toward the fixed jaw, for web gripping purposes, when the roller 56 is on the low radius of the cam, but when said roller is on the high radius of the cam the jaw 53 thereby is positively spread apart from the fixed jaw to release the web.

In Fig. 3 the upper blade 47 on roller 5 and the upper socket on roller 4, are shown approaching each other from points equi-distant with relation to the point X at which they will arrive simultaneously, the jaws being spaced apart because their respective rollers 56 are still upon the high radius of the cam. At this point X the blade will begin to enter the socket pressing the web therein to form the fold at 60. Then as the rotation of rollers 4, 5 continues the roller 56 enters the low radius of the cam, thereby closing jaw 53 on the entered web portion and allowing spring 57 to press said jaw against the fold to accentuate and grip it.

The interengagement of the blade and socket is complete when these elements are aligned in a plane through the axis of shafts

2, 3, the fold in the web being then pressed fully into the socket to the depth of the blade. From this point onward in the continued rotation of rollers 4, 5 the blade and socket gradually separate, leaving each other at about the point Z, but the web fold remains gripped by the jaws under the tension of spring 57 until roller 56 rides up upon the high radius of the cam, swinging jaw 53 to its open position and thereby releasing the web fold, which then falls upon the table as shown in Fig. 1, to create a stack of connected leaves.

The folds are produced in the manner described alternately in the rollers 4, 5, so that the web portions bounded by succeeding folds, fall successively from opposite sides to build up upon the table a stack comprising a series of connected leaves. The blade 47 that presses a fold of web into a socket thereby indents or weakens the web in the line of the blade edge contact, giving the web the effect of its being divided into a succession of hinged leaves, capable of falling individually into stack formation when the web is released alternately from above opposite ends of the stack, as clearly shown in Fig. 1.

As shown in Fig. 6, the blade edge may be serrated or provided with saw teeth 61, to deeply indent or perforate the line of blade contact upon the web, to thus enhance the hinge effect referred to.

The table 62, placed alongside table 11 is intended for the transference thereon of completed stacks of folded web, for the purpose of shearing said stacks by known means into widths suitable for use in recording machines.

Variations within the spirit and scope of our invention are equally comprehended by the foregoing disclosure.

We claim:

1. The method of producing a stack of connected leaves of paper from a web thereof which consists in communicating continuous travel motion to said web from its supply source, applying moderate tension to said web to create forward slack therein, guiding the slack web under moderate tension to an elevated position, then allowing the web to pass vertically downward to a given point, indenting said web at said point, alternately at opposite sides thereof in succession, to create folds therein, permitting said folds to fall into a stack thereof, and finally shearing the stacks into suitable widths for the purpose specified.

2. The herein described machine comprising a frame adapted to support a supply roll of paper web revolvably mounted thereon, a pivotal guide roller also mounted on said frame, above said supply roll, tensional means co-acting with said guide roller permitting the web to fall therefrom in a slack loop, tensional guide means in an elevated position upon the frame for the slack por-

tion of the web, a drum journalled on the frame to support the web leaving the elevated guide means, a pair of rollers journalled on the frame and having their peripheral surfaces in opposed relation to receive between them the web leaving said drum, means on said pair of rollers to indent the web passing therebetween alternately at opposite sides thereof, a table located below said pair of rollers to receive said web as it falls thereon in a stack of connected leaves, a train of gears to drive said rollers and drum, and means for operating said train.

3. The herein described machine comprising a frame adapted to support a supply roll of paper web revolvably mounted thereon, a pivotal guide roller, also mounted on said frame, above said supply roll, tensional means co-acting with said guide roller permitting the web to fall therefrom in a slack loop, tensional guide means in an elevated position upon the frame for the slack portion of the web, a drum journalled on the frame to support the web leaving the elevated guide means, 20 a felt covered roller co-acting with the drum to frictionally retard the web over the latter, a pair of rollers journalled on the frame and having their peripheral surfaces in opposed relation to receive between them the web leaving said drum, means on said pair of rollers to indent the web passing therebetween alternately at opposite sides thereof, a table located below said pair of rollers to receive said web as it falls thereon in a stack of connected 25 leaves, a train of gears to drive said rollers and drum, and means for operating said train.

4. The herein described machine comprising a frame adapted to support a supply roll of paper web revolvably mounted thereon, a pivotal guide roller, also mounted on said frame, above said supply roll, tensional means co-acting with said guide roller permitting the web to fall therefrom in a slack loop, tensional guide means in an elevated position 40 upon the frame for the slack portion of the web, a drum journalled on the frame to support the web leaving the elevated guide means, a pair of rollers journalled on the frame and having their peripheral surfaces 45 in opposed relation to receive between them the web leaving said drum, means on said pair of rollers to indent and grip the web passing therebetween alternately at opposite sides thereof, means for releasing the grip 50 upon the web successively from opposite points of said rollers, a table located below said pair of rollers to receive said web as it falls thereon in a stack of connected leaves, a train of gears to drive said rollers and drum, 55 and means for operating said train.

Executed this 2nd day of January, 1929.
